UNITED STATES PATENT OFFICE.

WILLIAM H. FIKE, OF IBERIA, MISSOURI.

INHALER.

SPECIFICATION forming part of Letters Patent No. 657,866, dated September 11, 1900.

Application filed May 17, 1900. Serial No. 16,996. (No model.)

To all whom it may concern:

Be it known that I, WILLIAM H. FIKE, a citizen of the United States, residing at Iberia, in the county of Miller and State of Missouri, have invented new and useful Improvements in Inhalers, of which the following is a specification.

My invention relates to improvements in inhalers, and contemplates the provision of an inhaler through which a large volume of medicine-laden air may be drawn into the nose or mouth at each inspiration and one embodying such a construction that it may be quickly and easily replenished with medicated absorbent when necessary.

With the foregoing in mind the invention will be fully understood from the following description and claims when taken in conjunction with the annexed drawings, in which—
20 Figure 1 is a longitudinal central section, on an enlarged scale, of my improved inhaler. Fig. 2 is a transverse section taken in the plane indicated by the broken line 2 2 of Fig. 1. Fig. 3 is a detail transverse section taken 25 in the plane indicated by the broken line 3 3 of Fig. 1. .

Similar letters of reference designate corresponding parts in all of the views of the drawings.
30 In the present and preferred embodiment of my invention the inhaler-casing A is of T form, and comprises a body a, of circular form in cross-section, and a stem b, of similar form in cross-section, which extends laterally 35 from the body, preferably at the middle thereof, as shown in Fig. 1. The ends of the body a and the outer end of the lateral stem b are designed to be normally closed by removable caps c, as illustrated, so as to prevent the escape of the medicament employed when the inhaler is not in use.

Within the body a and stem b of the casing A are arranged removable foraminated cylinders B C, respectively, the said cylinders being preferably of the proportional lengths and diameters illustrated. The cylinder B is provided at or adjacent to its ends with foraminated diaphragms d, and the cylinder C is provided adjacent to its outer end 45 with a foraminated diaphragm e, which diaphragms are designed to permit the free passage of air, and yet exclude dust and other

foreign substances from the interior of the inhaler. The cylinder B is also preferably provided at its middle with an aperture f, which is designed to coincide with the concave inner end of the cylinder C, as shown in Figs. 1 and 3, and permit of the free passage of air from the cylinder B to cylinder C, and vice versa. While it is preferable the aperture f is not essential, inasmuch as when deemed expedient the smaller apertures of the cylinder B may be depended upon to effect communication between the two cylinders.

Surrounding the cylinders B C and interposed between said cylinders and the body and stem, respectively, of the casing A are sections D E, of absorbent material. These sections D E are preferably in the form of wrappings of blotting-paper, textile, raw cotton, or other material susceptible of being readily impregnated with the medicament which it is desired to employ, and the section D is provided with an aperture g coincident with the end of section E, as shown, so as not to interfere with the free passage of air from the cylinder B to the cylinder C, and vice versa. When desirable it is obvious that in lieu of employing wrappings of absorbent material around the cylinders B C cylinders 80 of absorbent material may be interposed between said cylinders B C and the casing, or loose absorbent material may be packed between the same and the casing. In either case it will be observed that when the cylinders B C are withdrawn from the casing the absorbent material may be readily removed to be reimpregnated with medicament or give place to fresh medicated absorbent, and it will also be observed that when the sections of absorbent material are in the form of wrappings or cylinders they may be readily placed on the cylinders B C and shoved with the same into the body and stem, respectively, of the casing. When the foraminated cylinders and 95 the sections of absorbent material are placed in the casing, as stated, it will be observed that the cylinders will securely retain the absorbent material in position, and yet will permit the fumes from the same to freely mingle with the air drawn through the body and stem of the casing, and it will also be observed that the frictional contact between the absorbent and the casing and foraminated cyl-

inders will tend to hold the latter against casual movement or displacement without interfering with them, being readily removed when desired.

5 I prefer in practice to cast the casing, foraminated cylinders, and caps of my improved inhaler of aluminium or other suitable metal, although it is obvious that they may be made of wood or other material suitable to the purpose.

10 In using the inhaler the caps *c* are removed and the end of the stem *b* of the casing is placed in one nostril and the other nostril is closed, after which air is drawn through the 15 device into the nose. When air is thus drawn through the device, it will pass from the opposite ends of the casing-body *a* and thence up the stem *b* in large volume and incident to its passage will take up the fumes of the 20 medicament given off by the absorbent material and convey the same to the seat of disease in the nasal passages. When it is desired to inhale the medicated air through the mouth, the operation described is repeated, 25 with the exception that one end of the casing-body *a* is placed in the mouth. In either case it will be noticed that air enters the casing *A* at two points, and hence a large volume of the same is drawn through the foraminated 30 cylinders, in which it is free to take up the fumes given off by the medicated absorbent, and into the head of the patient.

Having thus described my invention, what I claim is—

1. An inhaler comprising a casing having 35 a body open at its opposite ends, and a stem communicating with and extending laterally from the body at an intermediate point in the length of the latter and open at its outer end, a foraminated cylinder arranged in the body 40 of the casing, a foraminated cylinder arranged in the stem of the casing and communicating with that in the body, and absorbent material interposed between the foraminated cylinders and the body and stem of the casing 45 substantially as specified.

2. An inhaler comprising a casing having a body open at its opposite ends, and a stem communicating with and extending laterally from the body at an intermediate point in the 50 length of the latter and open at its outer end, a foraminated cylinder removably arranged in the body of the casing, a foraminated cylinder removably arranged in the stem of the casing, and absorbent material interposed between the cylinders and the body and stem of the casing and removable therefrom; said absorbent material being held in position by the cylinders and adapted to hold said cylinders against casual movement or displacement, substantially as specified. 55

In testimony whereof I have hereunto set my hand in presence of two subscribing witnesses.

WILLIAM H. FIKE.
